Primary Examiner — L. A. Grabenstetter*Assistant Examiner* — Danielle Nichole Bowly*(74) Attorney, Agent, or Firm* — MCGINN I.P. LAW GROUP, PLLC(57) **CLAIM**

The ornamental design for a printer as shown and described.

DESCRIPTION

FIG. 1 is a front view of a printer showing our new design;

FIG. 2 is a rear view of the printer;

FIG. 3 is a top plan view of the printer;

FIG. 4 is a bottom plan view of the printer;

FIG. 5 is a right view of the printer;

FIG. 6 is a left view of the printer; and,

FIG. 7 is a perspective view of the printer.

The broken lines shown in the drawings represent portions of the printer that form no part of the claimed design.

1 Claim, 7 Drawing Sheets(56)
